UNITED STATES PATENT OFFICE.

MICHAEL P. KEALY, OF JERSEY CITY, NEW JERSEY.

PAVING-BLOCK.

1,884,101.

Specification of Letters Patent. Patented Mar. 16, 1920.

Application filed April 16, 1919. Serial No. 290,419.

To all whom it may concern:

Be it known that I, MICHAEL P. KEALY, a citizen of the United States, and a resident of Jersey City, in the county of Hudson and State of New Jersey, have invented a new and Improved Paving-Block, of which the following is a full, clear, and exact description.

The present invention relates to new and useful improvements in pavements, and pertains more particularly to pavements constructed from wooden blocks.

It is the primary object of the present invention to provide means by which the blocks are spaced with relation to each other, said means also serving to maintain said blocks in their proper position during the operation of laying the pavement.

Pavements of this type as at present laid also present a very slippery surface in wet weather, and it is a further object of the present invention to space the blocks the necessary distance to permit of the insert of a grout or other suitable material in sufficient quantity to present surface enough between the blocks to obviate this objectionable feature.

It is a further object of the invention to provide a device of this character which is simple in construction and cheap of manufacture.

With the above and other objects in view, reference is to be had to the accompanying drawings in which—

Figure 1 is a top plan view of a portion of a pavement constructed in accordance with the present invention.

Fig. 2 is a perspective view of the spacing element.

Referring more specifically to the drawings, and particularly to Fig. 1, the reference character 10 designates wooden blocks, such as those employed in laying wooden pavements, and said blocks are laid in lap-joint relation to each other with an intervening space 11 between their adjacent sides and ends.

The blocks 10 are maintained in spaced relation to each other by means of a metallic clip 12 of special construction to particularly adapt it to this purpose. This clip 12 is substantially U-shaped and comprises a body portion 13, from which projects two parallel legs 14. As shown in Fig. 2, the body portion 13 is cut out, as at 15, to pro-

vide a projecting member 16, which extends from said body portion 13 in a direction opposite to the legs 14. This cut-out portion extends throughout only approximately one-half of the lateral dimension of said body portion to prevent weakening thereof, and, at the same time, provide a projecting member which will be capable of performing the function desired.

The outer or free end of each of the legs 14 is angularly cut, as at 17, to provide a driving point 18, and an outwardly disposed wing or like member 19.

In use, the blocks 10 are positioned as shown in Fig. 1, with the metallic spacing elements 12 previously secured thereto. In securing these spacing elements, the driving members 18 are forced into the sides of their respective blocks until the outwardly bent members 19 engage the side face of the block and prevent further driving of the spacing element 12.

When the spacing element 12 has been secured in place, the next adjacent block is placed with one of its ends in engagement with the member 16, as shown at 20 in Fig. 1.

If this system of laying the blocks is followed, it will be seen that a space 11 will be provided, which space will entirely surround each respective block.

After the several blocks have been positioned, the space 11 is filled with any suitable grout, said space being of sufficient dimensions to present a surface of grout which will eliminate skidding and slipping on a pavement constructed as above described. Furthermore, sufficient quantity of grout will be employed to permit of ready expansion of the blocks under varying conditions of moisture.

Having thus described the invention what is claimed as new is:

1. A pavement comprising a plurality of blocks laid in spaced and lap joint relation, means carried by one of said blocks intermediate of its ends for maintaining said spaced relation, and means carried by said spacing means and integral therewith for engaging one of the ends of one of the adjacent blocks of said pavement.

2. A device of the character described comprising a substantially U-shaped member, driving points formed on the free end of each of the legs of the U-shaped member, and block engaging means integral with the 110

body portion of said U-shaped member, said block engaging means disposed at right angles to said body.

3. A device for spacing blocks comprising a substantially U-shaped member, driving points integral with the free end of each of the legs of the U-shaped member, means integral with each of said legs and projecting at right angles thereto for limiting the depth of the driving members, and block

engaging means carried by the body portion of the U-shaped member.

4. A spacing element for blocks comprising a substantially U-shaped member, block attaching means formed on the free end of each of the legs of the U-shaped member, and block engaging means integral with the body portion of the U-shaped member and projecting at right angles thereto. 15

MICHAEL P. KEALY.
